UNITED STATES PATENT OFFICE.

HOWARD AUSTIN WHITESIDE, OF NEW YORK, N. Y.

HELICO-PLANE.

Application filed February 18, 1920, Serial No. 359,553. Renewed April 30, 1924.

To all whom it may concern:

Be it known that I, HOWARD A. WHITESIDE, a citizen of the United States, residing at New York, in the county of New York and State of New York, have invented certain new and useful Improvements in Helico-Planes, of which the following is a full, clear, and exact description, such as will enable others skilled in the art to which it appertains to make and use the same.

This invention relates to airships of the heavier than air class, and with respect to some of its more specific details to that type known as helicopters and aeroplanes.

One object of this invention is to provide an aeroplane with improved means for directly lifting it upwardly into the air without any preliminary run along the ground.

Another object is to provide an aeroplane with an improved means for sustaining it in substantially stationary position in the air.

Another object is to provide an improved means for directly lifting an aeroplane in flight into the air, for sustaining it in position in the air or for effecting substantially vertical descent without any direct action of sustaining air currents on the wings.

Another object is to provide an aeroplane with means of improved construction for lifting the aeroplane or sustaining it in flight or for propelling it forwardly or rearwardly through the air.

Another object is to provide an aeroplane with improved propelling means in which the direction of the propelling effort is readily adjustable.

Another object is to provide a wing for an aeroplane with improved means whereby very little resistance is offered to upward or downward movement through the air and which may be adjusted so as to form an efficient sustaining surface for an aeroplane in flight.

Other objects of the invention will be in part obvious and in part pointed out hereinafter in connection with the following detailed description.

The invention accordingly consists in the features of construction, combinations of elements and arrangements of parts which will be exemplified in the construction hereinafter

set forth, and the scope of the application of which will be indicated in the following claims.

In the accompanying drawing wherein several illustrative embodiments of the invention are shown—

Figure 1 is a side elevation of a biplane with the invention applied thereto;

Fig. 2 is a front elevation of Fig. 1;

Fig. 3 is a detailed sectional view of the means for transmitting power from the motor to the lifting propellers;

Fig. 4 is a top plan view of a portion of a wing showing the tilttable panels and means for operating the same, certain parts being shown in section to more clearly show the invention;

Fig. 5 is a front elevation of Fig. 4, parts being broken away to show the operating mechanism for tilting the wing panels;

Fig. 6 is a detailed sectional enlarged view of a portion of the operating mechanism for the wing panels;

Fig. 7 is a view of a hand-operating lever for operating the wing panels;

Figs. 8 and 9 are sectional views showing portions of the mechanism for changing the angular position of the lifting propellers;

Fig. 10 is a front elevation showing a modification of the power connections;

Fig. 11 is a detailed fragmentary view of the gear connections used in the modification of Fig. 10; and

Fig. 12 is a perspective view of a tandem biplane with the invention applied thereto.

Referring now to the drawings for a detailed description of the invention, an aeroplane of the biplane type is shown in Figs. 1 and 2. As shown, this biplane has upper and lower wings or planes 1 and 2, a fuselage 3 having a cockpit or pilot's compartment 4, a tractor flight propeller 5, a chassis or landing gear 6, and steering rudders 7 and 8. All these parts may be of any standard or approved construction though in the present embodiment a special type of wings is employed.

In order to enable the aeroplane to rise from the ground without a preliminary run along the surface thereof, and to enable it to remain in substantially stationary posi-

tion in mid-air, or to descend substantially vertically without a downward gliding movement, direct lifting propellers or screws are provided. In the embodiment illustrated, 5 two of these propellers 9 and 10 are employed, being driven through suitable power transmitting connections from the driving motor. As shown in Fig. 2, these lifting propellers are mounted adjacent to the opposite ends of the upper wing at the entering edge thereof on short shafts 11 and 12 respectively. As the mountings for the shafts 11 and 12 are similar in construction only one need be described in detail. As 10 shown in Fig. 3, the shaft 12 is mounted in suitable bearings in a gear casing or box 13 and carries a bevel gear 14 rigidly secured thereto, meshing with a similar bevel gear 15 rigidly secured to a shaft 16 extending 15 adjacent the forward edge of the upper wing. The shaft 16 is preferably made hollow in order to secure the least weight consistent with the required strength.

Gear housing 13 is suitably rigidly secured 20 to a hollow tube 17 which encases the driving shaft 16, said tube being rotatable on said shaft and connected to a similar tube 17 by a transmitting connection 18 shown in detail at the left side of Fig. 3. This connection comprises a hub 19 secured rigidly at the end of the tube 17 and having an arm 20 projecting radially therefrom and connected at its outer end by a rod 21 to the outer end of a similar crank arm 20' 25 which is connected in similar manner to the tube 17'. It will be obvious from Figs. 2 and 3 that the tube 17' is connected at its outer end to the gear casing 13', the gear casings 13 and 13' thus being rigidly connected through the tubular casing 17 and 17' to rotate in unison. The shaft 16 and tubular casings 17 and 17' are carried by suitable bearings 22' and 23' carried by the forward truss of the aeroplane.

Intermediate the ends of shaft 16 is a gear casing or box 24 suitably supported by bearings 25 and 26 which are rotatably mounted in the hubs 19' and 19. This casing houses a bevel gear 27 rigidly mounted 50 on the shaft 16 and meshing with a second bevel gear 28 which is rigidly mounted on a hollow shaft 29; the latter being suitably connected to the driving motor of the aeroplane.

Disposed on one of the tubular sections, as 17', is a housing 30 enclosing a segmental gear 31 rigidly mounted on said section and meshing with a worm 32 carried by a vertically disposed shaft 33 mounted in suitable bearings and carrying a hand-operated means 34 at its lower end.

For the purpose of furnishing a strong and rigid structure for the support of the lifting propellers and the driving mechanism therefor a truss frame is provided as

shown in Fig. 2. This truss frame has upper and lower chords 35 and 36 respectively, and struts 37 extending therebetween. Tie rods or wires 38 secured to the upper and lower chords may also be provided to more rigidly secure the parts in operative alignment. 70

When the plane is moving upwardly or downwardly under the influence of the lifting propellers it is desirable that the air 75 resistance to such movement offered by the wings, or other parts, be reduced to a minimum. For accomplishing this purpose a wing construction is provided which is particularly shown in the detailed views of 80 Figs. 4, 5, and 6. As shown in Fig. 4, the wing surface, or a large portion thereof, is made up of movable sections 40 and 40' mounted in openings in the wing. These sections are mounted on pintles or stub 85 shafts 41, 42 which are disposed at one side of the longitudinal center line of each section, the sections 40 being mounted at one side of the center of length of the wing and sections 40' at the other side thereof. As 90 Fig. 4 shows a central portion of a wing, the center of length being indicated at c, it will be noted that the tilting sections on opposite sides of said center of length are reversely mounted on their respective stub shafts so that all the panels are overbalanced on their edges remote from the center of length.

Stub shafts 42 extend through and are supported in the walls of a longitudinal 100 frame member 43, which may be the front spar of the wing, passing through the interior of the frame member where suitable means are provided for operating the sections. As shown this operating means may 105 comprise longitudinal movable rack bars 44, 45, disposed in said hollow frame member and having toothed sections 46 engaging pinions 47 rigidly mounted on the shafts 42. At their adjacent ends, the rack bars 110 44 and 45 are connected by links 48 to the opposite ends of a double crank arm 49 carried by an operating shaft 50. The shaft 50 is suitably mounted and may be manually operated by a lever 51 which is 115 adapted to be locked in adjusted position by the engagement of a pawl with the toothed sector 52 as shown in Fig. 7 of the drawing.

The sections 40 and 40' are provided at 120 their edges remote from the center of length of the wing with suitable stops 53 which engage the margins of the apertures to hold the sections firmly in the plane of the wing under the influence of the lifting force of 125 the air impinging on the lower surface thereof.

The operation of the apparatus thus far described is as follows: When it is desired 130 to rise from the earth for flight into the

air, the hand lever 51 is adjusted to operate the rack bars 44 and 45 to move the wing sections 40 and 40' into substantially vertical positions, so that the edges thereof carrying the stops 53 move downwardly as shown by the dotted lines in Fig. 5. The shaft 33 is then operated by any suitable manual or power means to adjust the lifting propellers 9 and 10 into horizontal position 10 as shown in Fig. 2. When the lifting propellers are moved into this position it will be noted that the worm and gear construction particularly shown in Fig. 8 acts to positively lock the propellers in adjusted 15 position. The power for adjusting the propellers is transmitted through the hollow casing 17' to gear box 13' and through hollow casing 17', connections 20', 21 and 20, and hollow casing 17 to gear box 13, so that 20 the lifting propellers at both sides operate to adjusted position in unison. The lifting propellers may then be started to exert lifting force on the aeroplane, and the propeller speed is increased until sufficient force is 25 exerted to lift the plane from the ground. The main propeller 5 may be started up as desired to propel the machine in a horizontal direction when the desired altitude has been reached, and the wing sections 40 and 40' 30 may also be restored to normal positions. Both the lifting and the driving propellers are driven from the motor through suitable clutch mechanisms which may be released or set at will. It will also be obvious that the 35 lifting propellers may be operated if desired without tilting the wing sections, but in this case the air resistance will be relatively great. The lifting propellers may then be moved to vertical position, as shown, in 40 dotted lines in Fig. 1, so as to assist the main flight propeller in driving the aeroplane through the air. If desired the main propeller may be omitted entirely and the lifting propeller utilized for performing the 45 functions thereof. It is also obvious that the propellers 9 and 10 may be adjusted to any position intermediate the horizontal and vertical positions shown in Fig. 1 so that the effort may be utilized both to lift the aeroplane into the air and to propel it laterally 50 therethrough; they may also be adjusted so as to exert backward effort, so that rearward movement of the plane may be effected. Inasmuch as the tiltatable wing sections are 55 mounted off center, the force of the air currents impinging the under side of the wing in normal conditions of flight tends to hold each section firmly in its seat, the stops 53 holding it from moving beyond the plane of 60 the wing. It will be further noted that the sections 40 and 40' are reversely mounted at opposite sides of the center of length of the wing, and that they are rotated in opposite directions when tilted from normal position 65 so that the balance of the plane is main-

tained at all times. It will be clear that the lifting propellers may be employed to lower the machine from the air by driving them just below the speed required to sustain the machine in the air, whereupon it will descend slowly by gravity, or the same propellers may be employed to sustain the machine in substantially stationary position in the air by driving them at the proper speed to supply just enough force to sustain the 70 weight of the machine without any resulting upward or downward movement. For this purpose the line of resultant effort of the lifting propellers should pass through the center of gravity of the aeroplane. 75

In the modification shown in Figs. 10 and 11 the two lifting propellers 9^a and 10^a are driven respectively through inclined shafts 16^a and 16^b extending from the main driving motor to the respective gear boxes 80 or casings 13^a and 13^b through suitable gear connections in which the propeller shafts 11^a and 12^a are driven. In this construction there is a projecting box 60 on the side of each gear box, the purpose of which is to 85 house two intermeshing gears 61 and 62 rigidly mounted respectively on inclined shafts 16^a (or 16^b) and a short shaft 63, which is mounted in suitable bearings in the gear box. These short shafts carry 90 bevel gears 15^a meshing with bevel gears 14^a rigidly mounted on the propeller shafts. This construction provides means for allowing the gear boxes 13^a and 13^b to rotate with the propellers in vertical planes without any 95 binding of the driving gears. 100

As shown in Fig. 10, gear boxes 13^a and 13^b with the lifting propellers carried thereby are rotated in vertical planes by means similar to that shown in Figs. 1 and 2. 105 This means includes a shaft 33^a in driving relationship with a gear in the housing 30^a. These connections being similar to those shown in Fig. 8 need not be described in detail here. An operating bar 64 is connected at opposite ends to gear boxes 13^a and 13^b, and intermediate the ends thereof it is connected to the gear mechanism which is operated by means of shaft 33^a. It will thus be seen that the bar 64 is movable 110 bodily parallel to its longitudinal axis to rotate the gear boxes and the lifting propellers. 115

As shown in Fig. 10, a suitable truss frame may be furnished for supporting the power 120 transmitting gear for the propellers. This may comprise an upper stress member 65 and lower stress members which may be in the form of tubular casings surrounding shafts 16^a and 16^b, or the shafts may themselves be employed as lower stress members. Struts 66 extend between the upper and lower stress members to rigidly brace the 125 frame. 130

In the modification of Fig. 12 tandem 130

wings 70 and 71 are arranged on a common fuselage 3^b, each wing being constructed as described in connection with Figs. 4, 5, and 6 above, and the movable sections thereof being controlled from the pilot's cockpit 4^b by any suitable operating mechanism. According to this modification lifting propellers 72, 73 are mounted adjacent the forward wing and similar propellers 74 and 10 75 are mounted adjacent the rear wing. The propellers adjacent each wing are adapted to be rotated simultaneously in vertical planes by an operating gear similar to that described above. These propellers may 15 therefore act to lift the aeroplane or to propel it horizontally in flight as particularly described above in connection with the modification shown in Figs. 1 to 6.

For the purpose of securing stability in 20 all the modifications of the invention, the adjacent lifting propellers are connected to rotate in opposite directions. This is indicated by the arrows in Fig. 12 which show that the adjacent propellers both laterally 25 and fore and aft rotate in opposite directions.

The operation of the modification shown in Figs. 10 and 12 is similar to that of Figs. 1 to 6 which has been particularly described 30 above. This operation will therefore be clear to those skilled in the art, and need not be described in detail.

As many changes could be made in the above construction and many apparently 25 widely different embodiments of this invention could be made without departing from the scope thereof, it is intended that all matter contained in the above description or shown in the accompanying drawings shall 40 be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I 50 claim as new and desire to secure by Letters Patent is:

1. In an aeroplane, in combination, a fuselage having a traction propeller at one end thereof, a sustaining plane extending laterally from said fuselage, a second sustaining plane spaced vertically from said first plane, a lifting propeller spaced vertically from one of said planes, means for adjusting said lifting propeller to a position laterally disposed from one of said planes, and means on one of said planes for varying the resistance to upward or downward movement.

2. In combination with an aeroplane of 65 the biplane type having superposed sustain-

ing planes, a fuselage, a flight propeller at one end of said fuselage, a lifting propeller adjacent one lateral edge of one of said planes, means for adjusting the direction of effort of one of said propellers, means for locking said propeller in adjusted position, and means on one of said planes to vary the resistance to upward or downward movement.

3. In combination with an aeroplane of 75 the biplane type, sustaining planes for said aeroplane, a flight propeller, a lifting propeller, one of said propellers being adjustable so as to exert forward, backward or vertical effort upon said aeroplane, and means mounted on one of the planes of said aeroplane to vary the resistance to upward or downward movement.

4. In an aeroplane, in combination, a wing having a rigid frame including a longitudinally disposed hollow frame member, a plurality of movable sustaining panels mounted in said frame and having operating extensions extending into said hollow member, operating connections for said panels mounted within said hollow frame member, and operating mechanism operable from the pilot's cockpit for tilting said panels.

5. In an aeroplane, in combination, a wing having a rigid frame including a longitudinally disposed hollow frame member, a plurality of movable sustaining panels mounted in said frame and having operating extensions extending into said hollow member, pinions carried by said operating extensions and disposed in said hollow frame member, a rack carried in said hollow frame member, and operating mechanism operable from the pilot's cockpit to control said rack whereby to operate said sustaining panels.

6. In an aeroplane, in combination, a fuselage having a tractor propeller mounted thereon, a sustaining wing extending on opposite sides of said fuselage, movable sustaining panels mounted on said plane, a propeller mounted near the forward edge of said plane and adapted to rotate in a plane substantially parallel to that of said wing, means adapted to move one or more of said panels and thereby reduce or increase the effective sustaining area of said wing, and means adapted to swing said propeller into a position such that its plane of rotation is substantially normal to that of said wing.

7. In an aeroplane, in combination, a fuselage having a tractor propeller mounted thereon, a sustaining plane extending on opposite sides of said fuselage, movable sustaining panels mounted on said plane, propellers mounted near the forward edge of said plane and on opposite sides of said fuselage and adapted to rotate in a plane substantially parallel to that of said sustaining plane, said last mentioned propellers

being adapted to swing so as to rotate in a plane spaced above said sustaining plane or to rotate in a plane at an angle to said sustaining plane in a position laterally disposed from the latter, means to rotate said propellers including driving gears, a driving shaft operatively connecting the same, means to swing said propellers including

swinging gear boxes and a propeller shaft mounted therein to swing with the same. 10

In testimony whereof I affix my signature, in the presence of two witnesses.

HOWARD AUSTIN WHITESIDE.
